HINGE FOR GRAIN DRILL HOPPERS

Ronald E. Penfold, Aldershot, Ontario, Canada,
assignor to International Harvester Company,
a corporation of New Jersey

Application February 13, 1953, Serial No. 336,814

6 Claims. (Cl. 220—31)

1

This invention relates to hoppers for grain drills and the like and particularly to a novel hinge construction for the hopper lid.

A hopper for a grain drill, fertilizer distributor or the like, is generally an elongated box customarily made of relatively light sheet metal mounted upon a wheeled frame extended transversely of the direction of travel and drawn by a tractor or other source of power. The box is provided with a lid which is hinged along one side so that it can be raised when the hopper is to be filled. In the past the conventional hopper lid was mounted on the box by a pivoting member attached to the lid and passed through an opening in the wall of the box. This construction provided a hinge and also prevented relative displacement between the main part of the hopper and the lid. This construction had the disadvantage that it allowed moisture to enter the opening provided in the box, contaminating the contents. More recently, this disadvantage has been avoided by securing a hinge loop at several locations longitudinally of the box and providing rolled beads at the adjacent edges of the lid hopper interlocked with the hinge loop to form the hinge. One of the disadvantages inherent in this construction was the tendency, in operation, of the lid to become displaced longitudinally relative to the main part of the hopper. Another disadvantage was that in loading the hopper with grain, or the like, the latter tended to lodge between the hinge loop and the lid and create an obstruction upon closing the lid, resulting in distortion thereof.

The present invention was designed to overcome the foregoing difficulties and has for its principal object the provision of an improved hinge construction for attaching the lid to the hopper of a grain drill or the like.

Another object of the invention is the provision of an improved hinge structure for a grain hopper or the like, wherein means are provided for preventing relative displacement of the lid and the main body of the hopper, and for avoiding the deposition of seed between the lid and the edge of the box adjacent the hinge.

Another object of the invention is the provision of a cover for the hinge of a grain drill hopper lid to prevent accumulation of material between the lid and the hinge loop and having flanges engaging the sides of the hinge loop to prevent displacement of the lid from the hopper body.

Other objects and advantages of the invention will become clear from the following detailed description when read in conjunction with the accompanying drawings, wherein:

2

Fig. 1 is a schematic view partly in section of one end of a grain drill hopper incorporating the features of this invention.

Fig. 2 is an enlarged detail of the hinge construction without the hinge cover showing the manner in which grain is deposited in the loop formed at the edge of the box lid;

Fig. 3 is an enlarged detail in section of the hinge construction embodied in the present invention with the hinge cover thereon, and

Fig. 4 is a section taken on the line 4—4 of Fig. 3.

Referring now to the drawings it will be observed that the grain hopper of this invention is designated by the numeral 10 and is mounted upon a frame 11 which is more or less conventional and is adapted to be mounted upon wheels (not shown), whereby the implement is propelled over the ground. In Fig. 1 the grain box 10 of this invention is shown schematically but it may be understood it comprises end walls 12, one of which is provided at each end of the box, upright front and rear walls 13 and 14 respectively, a bottom 15 having suitable openings therein for a lid or cover 16.

Near the upper ends of the side walls 13 and 14 of the hopper, these walls slant inwardly to provide converging portions 17 and 18 terminating in rolled edges or beads 19 and 20 extending the entire length of the box.

There is also provided at the upper end of wall 14, and secured to the slanting upper end 17 thereof, a hinge member 21 affixed to the wall of the box by any suitable means such as one or more bolts 22. Hinge member 21 has an arcuately shaped loop portion 23 having a curvature conforming to the bead 20 and spaced therefrom to provide a socket 24.

The lid 16 has the edge thereof adjacent the side 14 of the main body of the hopper, bent to form a loop 25 and an arcuate hinge part 26 adapted for sliding reception in the socket 24 between the bead 20 of the part 23 of the hinge member 21 and defining a pocket 27 in the edge of the lid.

At this point it should be clear that a hinge has been provided between the hopper lid and the main body thereof permitting free swinging of the lid from closed to opened position and that upon opening the lid to its widest extent the projection formed by the loop 25 will engage the slanting upper edge of the hopper side 14 while the hopper is being filled. As shown in Fig. 2, however, without the provision of means for inhibiting it, grain frequently becomes lodged in

the pocket 27 and forms a lump between the lid and the hinge member 21 when the lid is closed. This makes closure difficult and results in distortion of the lid. In order to avoid this difficulty applicant provides a hinge cover or guard designated by the numeral 28 having a shank portion 29 secured to the lid by one or more bolts 30 and having a projecting portion 31 extending into the pocket 27 and filling the space between the lid 16 and the arcuate portion 23 of the hinge member 21.

The guard 28 also has an arcuate portion 32 shaped to fit over and spaced slightly from the portion 23 of the hinge member 24. There are likewise provided at opposite ends of the guard 28 and extending radially therefrom to overlap the sides of the hinge member 21, spaced flanges 33. These flanges are engageable with the sides of the hinge member 21 throughout the range of swinging the movement of the lid 16 relative to the main hopper body and prevent displacement of the lid from the hopper.

The operation of the improved hinge construction of this invention should be clearly understood from the foregoing description. It should likewise be understood that modifications may be made in the invention without departing from the spirit thereof or the scope of the appended claims.

What is claimed is:

1. In a hopper for grain drills and the like wherein elongated generally vertical side walls terminate at their upper ends in rolled beads spaced to form the hopper opening, a hinge member secured to the inner surface of one wall of the hopper having an arcuate portion spaced from and concentric with a portion of the bead at the end of said wall to form a socket, a lid adapted to cover the opening in the hopper having one edge curved downwardly and inwardly to form a loop pocket and terminating in an arcuate portion adapted to be received in said socket to provide a hinge, and a hinge cover member adapted to prevent depositing of grain between the lid and the hinge member comprising a part secured to the inner surface of the lid and an arcuate portion complementary to and covering the arcuate portion of said hinge member.

2. In a hopper for grain drills and the like wherein elongated generally vertical side walls terminate at their upper ends in rolled beads spaced to form the hopper opening, a hinge member secured to the inner surface of one wall of the hopper having an arcuate portion spaced from and concentric with a portion of the bead at the end of said wall to form a socket, a lid adapted to cover the opening in the hopper having one edge curved downwardly and inwardly to form a loop pocket and terminating in an arcuate portion adapted to be received in said socket to provide a hinge, and a hinge cover member adapted to prevent depositing of grain between the lid and the hinge member comprising a part secured to the inner surface of the lid and an arcuate portion complementary to and covering the arcuate portion of said hinge member and a projecting portion receivable in said loop.

3. In a hopper for grain drills and the like wherein elongated generally vertical side walls terminate at their upper ends in rolled beads spaced to form the hopper opening, a hinge member secured to the inner surface of one wall of

the hopper having an arcuate portion spaced from and concentric with a portion of the bead at the end of said wall to form a socket, a lid adapted to cover the opening in the hopper having one edge curved downwardly and inwardly to form a loop pocket and terminating in an arcuate portion adapted to be received in said socket to provide a hinge, and a hinge cover member adapted to prevent depositing of grain between the lid and the hinge member comprising a part secured to the inner surface of the lid and an arcuate portion complementary to and covering the arcuate portion of said hinge member, a projecting portion receivable in said loop, and spaced flanges projecting radially from the arcuate portion of said hinge cover and engageable with opposite ends of said hinge member to prevent axial displacement of the lid with respect to the hopper.

4. In a hopper for grain drills and the like wherein elongated generally vertical side walls terminate at their upper ends in rolled beads spaced to form the hopper opening, a hinge member secured to the inner surface of one wall of the hopper having an arcuate portion spaced from and concentric with a portion of the bead at the end of said wall to form a socket, a lid adapted to cover the opening in the hopper having one edge curved downwardly and inwardly to form a loop pocket and terminating in an arcuate portion adapted to be received in said socket to provide a hinge, and a hinge cover member adapted to prevent depositing of grain between the lid and the hinge member comprising a part secured to the inner surface of the lid and an arcuate portion complementary to and covering the arcuate portion of said hinge member, spaced flanges projecting radially from the arcuate portion of said hinge cover and engageable with opposite ends of said hinge member to prevent axial displacement of the lid with respect to the hopper and an extension of the arcuate portion receivable in said loop.

5. In a hopper for grain drills and the like having generally vertically extending side walls one of which has its upper edge rolled to form a bead, a hinge member secured to the inner surface of said wall adjacent the bead and having an arcuate portion spaced from and concentric with a portion of the bead to form a socket, a lid for the hopper having one edge curved downwardly and inwardly to form a loop and terminating in an arcuate portion adapted to be received in said socket to provide a hinge, and a guard member secured to the lid, said guard member having a projection receivable in said loop pocket to prevent the deposition of grain therein and an arcuate portion conforming to the shape of and partly covering said hinge member.

6. The invention set forth in claim 5, wherein the arcuate portion of the guard member is provided with flanges engageable with the ends of the hinge member to prevent axial displacement of the lid.
